CARBURETOR

Scott F. Hunt, Meriden, Conn., assignor, by mesne assignments, to Niles-Bement-Pond Company, West Hartford, Conn., a corporation of New Jersey

Application October 26, 1944, Serial No. 560,435

9 Claims. (Cl. 261—41)

1

The present invention relates to carburetors for internal combustion engines, and particularly to enrichment controls for such carburetors.

Most modern carburetors intended for use on aircraft engines are provided with a manual mixture or fuel-to-air ratio control by means of which the operator of the aircraft may select either a lean fuel-to-air ratio or a rich fuel-to-air ratio, depending upon the flight conditions encountered. Such carburetors are also usually provided with a device for automatically increasing the fuel-to-air ratio when the load on the engine exceeds a predetermined value. Such devices are commonly termed "enrichment controls."

Formerly, the enrichment control was usually set so that it operated to increase the fuel-to-air ratio when a definite engine load was exceeded, regardless of the setting of the manual mixture control. However, it has been found that a considerable fuel saving can be gained if the enrichment control is operated at a higher engine load when the mixture control is in its lean position than when the mixture control is in its rich position. Such operation of the enrichment valve permits the operation of the engine at higher engine loads with a lean fuel-to-air ratio. Therefore, the highest economical cruising speed is increased, and likewise the range of the aircraft on which such an arrangement is used.

In my copending application, Serial No. 498,151, filed August 11, 1943, I have illustrated an arrangement wherein the automatic enrichment occurs at different values of engine load, depending upon whether the manual mixture control is in its lean or rich positions.

It is an object of the present invention to provide an improved and simplified mixture and enrichment control of the type illustrated in my copending application referred to above.

Another object of the present invention is to provide an arrangement wherein the operating characteristics of a single enrichment valve are varied in accordance with the position of the manual mixture control.

Another object of the present invention is to provide an arrangement of the type described wherein the variation of the operating characteristics of the enrichment valve is accomplished by a device responsive to a fluid pressure which varies in accordance with the position of the manual mixture control.

Other objects and advantages of the present invention will become apparent from a consider-

2

ation of the appended specification, claims and drawing, in which

Figure 1 illustrates, somewhat diagrammatically, a carburetor for an internal combustion engine embodying the principles of my invention.

Figure 2 shows a cross-sectional view of a modified form of the enrichment control valve and operating mechanism therefor which may be used in the carburetor of Figure 1 to carry out

10 the principles of my invention, and

Figure 3 illustrates a modified form of mixture control valve which may be used in place of the mixture control valve of Figure 1.

Referring to the drawings, there is shown in

15 Figure 1 a body 10 of a carburetor for an aircraft type internal combustion engine. Air enters the carburetor body 10 at an inlet 12 and flows thru a Venturi restriction 14 and a passage 15, past a throttle 16 and a fuel discharge nozzle 18 to an outlet 20. A supercharger may be provided between the outlet 20 and the intake manifold of the engine. In certain cases the supercharger may be upstream from the inlet 12, or two superchargers may be used, one in each place.

25 The Venturi restriction 14 produces a pressure differential between the inlet 12 and the throat of the restriction which varies substantially in accordance with the square of the velocity of the air passing thru the restriction. Since the cross-sectional area of the venturi is constant, this pressure differential may be taken as a measure of the volume of air flowing thru the passage per unit time.

30 The pressure differential between entrance 12 and the throat of venturi 14 is utilized to create an air flow thru a secondary air passage extending from entrance 12 to the throat of venturi 14. A plurality of impact tubes 22 are provided, whose open ends project into the entrance 12 to receive

35 the impact of the entering air. The secondary air passage may be traced from entrance 12, thru tubes 22, a passage 24 interconnecting the impact tubes, a conduit 26, a chamber 28 in a pressure meter generally indicated at 30, a restriction 32, a chamber 34 in the pressure meter 30, a conduit 36, past a valve 38 into a chamber 40, and thence

40 thru a conduit 42 to the throat of venturi 14.

45 The valve 38 is operated by a sealed bellows 44 mounted in the chamber 40. The bellows 44 is fixed at one end, so that the position of the free end, to which valve 38 is attached, varies in accordance with the air pressure in the chamber 40. The bellows 44 is preferably filled with

50 nitrogen or some other suitable temperature responsive fluid, so that the position of valve 38

varies not only with the pressure but with the temperature of the air in the chamber 40, and hence with the density of that air.

In the secondary air passage, the pressure differential between the entrance 12 and the throat of venturi 14 is divided into two component pressure drops, one across the restriction 32 and the other across the valve 38. The valve 38, as previously mentioned, is positioned in accordance with the density of the air flowing thru the passage 15. Valve 38 is moved toward open position as the air density increases and toward closed position as the air density decreases. If the volume of air flowing per unit time thru passage 15 remains constant while its density decreases, then the mass of air flowing is decreased, but the pressure differential set up by the venturi 14 remains constant. However, the movement of valve 38 toward closed position causes the component pressure drop across valve 38 to increase, and the component pressure drop across restriction 32 to decrease, reflecting the decrease in the mass of air flowing. By proper design of valve 38, the pressure drop across restriction 32 may be made to vary substantially in accordance with the mass of air flowing thru passage 15. This pressure differential across restriction 32 acts on a diaphragm 46 which separates the chambers 28 and 34. The force applied to diaphragm 46 is transmitted to a valve 48, on which it acts in a closing direction.

The fuel enters the carburetor from a fuel pump or other source of fuel under superatmospheric pressure. It flows thru a conduit 50, a valve 52 in a pressure regulator 54, a conduit 56, a mixture control valve mechanism generally indicated at 58, a jet system 60, an idle valve 125, a conduit 62, a valve 64 in a pressure regulator 66, and a conduit 68 to the fuel discharge nozzle 18.

The pressure regulator 54 includes a diaphragm 70 separating a pair of expandible chambers 72 and 74 and connected at its center to the valve 52. A spring 76 biases the valve 52 toward open position. A restriction 78 connects the chambers 72 and 74.

A portion of the fuel entering pressure regulator 54 flows thru chamber 74, restriction 78, chamber 72, a conduit 80, a chamber 82 in the pressure meter 30, past the valve 48, and thru a conduit 84 to the main air passage 15. Alternatively, the conduit 84 may lead to the fuel tank, the fuel pump inlet, the fuel conduit 62, or elsewhere, as long as it leads to a point maintained at a pressure continuously lower than that in chamber 82.

The pressure meter 30 includes a diaphragm 86 separating the chambers 34 and 82 and a diaphragm 88 separating the chamber 28 from a fourth expandible chamber 90. The valve 48 is biased toward closed position by a spring 92.

The chamber 90 is connected thru a conduit 94 to the fuel conduit 62 downstream from the jet system 60. The pressure in chamber 90 is therefore the same as that in the fuel line downstream from the jet system. The pressure in chamber 82 is the same as that in chamber 72 of pressure regulator 54.

The position of diaphragm 70 and valve 52 is determined by the balance between the spring 76 plus the pressure in chamber 72 acting in a valve opening direction and the pressure in chamber 74 acting in a valve closing direction. If the balance between these forces is upset, the diaphragm 70 and valve 52 move, thereby varying the pressure in chamber 74 until the balance is

restored. Since the pressures in chambers 72 and 74, under equilibrium conditions, differ by a substantially constant amount dependent on the strength of spring 76, the pressure in chamber 72 may be used as a measure of the pressure in chamber 74, which is substantially the same as the pressure on the upstream side of the jet system 60.

For any given constant cross-sectional area of the fuel passages thru the jet system 60, the pressure differential across it is a measure of the fuel flow thru it. This pressure differential, or rather a smaller pressure differential which is a measure of the pressure differential across the jet system, is applied thru the diaphragms 86 and 88 of pressure meter 30 to the valve 48, on which it acts in an opening direction.

From the foregoing, it may be seen that the valve 48 is positioned in accordance with the balance between two forces, one of which varies in accordance with the mass of air entering the carburetor, and the other in accordance with the mass of fuel entering the carburetor. Furthermore, the valve 48 controls the mass of fuel entering the carburetor, since it controls the pressure in chamber 82. The pressure in the chamber 82 is transmitted to chamber 72 of pressure regulator 54 where it controls the position of valve 52 and hence the pressure on the upstream side of the jet system 60.

The pressure regulator 66 operates to maintain a substantially constant pressure on the downstream side of the jet system 60 and thereby to prevent variations in pressure at the fuel discharge nozzle 18, which may be due to operation of the throttle or to variations in engine speed, from reaching the downstream side of the jet system and effecting the fuel flow.

The pressure regulator 66 includes a pair of expandible chambers 96 and 98 separated by a flexible diaphragm 100, which is attached at its center to the valve 64. A spring 102 biases the valve 64 toward closed position. The chamber 96 is connected thru a conduit 104 to the conduit 26 and thence thru the passage 24 and impact tubes 22 to the air entrance 12. The chamber 98 is connected to the conduit 62.

The mixture control 58 includes a disc valve 106 fixed on a shaft 108. The disc valve 106 controls the flow of fuel thru ports opening into conduits 110 and 112 which lead into the jet system 60. When the disc 108 is in the position illustrated in full lines in the drawing, fuel can flow to the jet system only thru the conduit 110. This full line position of the disc valve 106 is known as the "lean" position of the mixture control 58. When the disc valve 106 is in the dotted line position shown in the drawing, the fuel can flow thru both the conduits 110 and 112. The dotted line position of disc valve 106 is termed the "rich" position of the mixture control. The disc valve 106 can also be moved to a "cut-off" position wherein it cuts off the flow thru both conduits 110 and 112.

The conduit 110 conducts fuel either thru a fixed restriction or jet 114, or thru a restriction 116 controlled by an enrichment valve 118 biased to closed position by a spring 120. The conduit 112 conducts fuel to a fixed restriction 122. Fuel flowing thru the restrictions 116 and 122 also flows thru another restriction 124 which limits the total flow thru restrictions 116 and 122. The enrichment valve 118 is normally closed, but opens at high pressure differentials across the jet system to increase the fuel-to-air ratio under heavy load conditions.

At very low air flows, such as are encountered under idling conditions, the pressure differential set up by the venturi 14 tends to be erratic, and is not a reliable indication of the volume of air entering the engine. Provision is made to control the fuel flow in accordance with the throttle position at such times. The spring 92 in the pressure meter 30 acts on valve 48 in a closing direction. When the differential pressure acting on diaphragm 46 is small, as under low air flow conditions, the spring 92 becomes the predominating force acting on valve 48. A closing movement of valve 48 causes an increase in the fuel flow thru the main fuel line, since the closure of valve 48 increases the pressure in chamber 82 of pressure meter 30 and hence in chamber 72 of pressure regulator 54. Furthermore, the spring 76 of pressure regulator 54 biases valve 52 in an opening or fuel flow increasing direction.

The idle valve 125 is pivotally attached to a lever 128, whose opposite end is connected by a link 130 to an arm 132 fixed on the shaft 134 of throttle 16. The idle valve is normally wide open when the throttle is beyond a range of positions near its closed position, usually termed the idling range. As the throttle moves into the idling range, thereby decreasing the air flow, the idle valve 125 moves toward closed position. At the same time, the springs 92 and 76 cause operation of valve 52 in an opening direction. The valve 52 is thereby opened sufficiently so that its restrictive effect on the fuel flow is less than that of the idle valve 125. Therefore the fuel flow under idling conditions is controlled primarily by the valve 125 in accordance with the position of the throttle, and not by the pressure meter 30 in accordance with the mass of air entering the engine.

A piston 119 is aligned with the stem of valve 118. The piston 119 is biased into engagement with the stem of valve 118 by a spring 121. One side of the piston 119 is exposed to the pressure in a cylinder which is connected thru a passage 123 to the conduit 112. The opposite side of piston 119 is exposed to the pressure of the fuel leaving the conduit 110.

When the mixture control 58 is in its lean position, as illustrated in full lines in the drawing, the valve 106 closes the conduit 112 so that the pressure in conduit 112 is substantially the same as the pressure on the downstream side of the jet system. This pressure is communicated thru conduit 123 to the left face of piston 119. The pressure acting on the right face of piston 119 is the pressure on the upstream side of the jet system. The piston 119 is therefore subject to a pressure differential which compresses spring 121 and holds the piston 119 separated from the stem of valve 118. When the mixture control is moved to the rich position, however, the conduit 112 is opened so that the pressures on both faces of piston 119 are equal. The spring 121 then moves piston 119 into engagement with the stem of valve 118, and applies an opening force to valve 118, opposite to the closing force of spring 120. Therefore, a smaller fuel pressure differential across the jet 116 is effective to overcome spring 120 and open valve 118 when the mixture control is in its rich position than when the mixture control is in its lean position. The valve 118 is therefore open at smaller engine load when the mixture control is in its rich position than when the mixture control is in its lean position.

While I have illustrated a particular type of carburetor, it will be appreciated by those skilled

in the art that my invention may be applied with equal facility to other types of carburetors. The carburetor illustrated may, for example, be modified by omitting the pressure regulator 54 and placing the valve 48 of the pressure meter 30 directly in the fuel line between the pump and the mixture control 58. This would require that the valve 48 be reversed so that it would open in a downward direction and close in an upward direction, the same as the present valve 52.

Figure 2

There is shown in Figure 2 a modified form of enrichment valve and control mechanism therefor which may be substituted for the valve 118 in Figure 1. Figure 2 also shows diagrammatically, a mixture control 58 and a jet system 60, which correspond to the same elements in Figure 1, and the connections between the new enrichment valve mechanism and the mixture control and jet system.

A casting 250 forms a part of the body of a carburetor. The casting 250 is hollow, having the chamber 252 formed therein. The upper and lower ends of chamber 252 are open, and a sleeve member 254 is inserted thru the upper end and extends therethru to the lower end. The lower end of sleeve 254 is internally threaded to receive an orifice plate or jet 256. The jet 256 is generally cylindrical. One end of jet 256 is open and forms a valve seat 258. The other end of jet 256 is provided with a central bushing 260, which is apertured to receive the stem 262 of a valve 264 which cooperates with the seat 258. The end of jet 256 which carries the hub 260 is also provided with a number of circumferentially spaced orifices 266. A spring retainer 268 is attached to the valve stem 262, and a spring 220 is retained between the retainer 268 and an external flange 270 on the bushing 260.

A diaphragm 219 has its edges clamped between the upper surface of sleeve 254 and the under surface of another sleeve 272. A cover plate 274 extends over the sleeve 272. The cover plate 274 is attached to the casting 250 by means not shown, and holds the sleeves 272 and 254 together. The interior of sleeve 272 forms a chamber 276. An elongated stem 278 is attached to the center of diaphragm 219. The upper end of stem 278 extends into a guide nut 280 at the upper end of sleeve 272. A spring 221 surrounds the stem 278 and is retained between the nut 280 and the diaphragm 219.

Below the diaphragm 219, the stem 278 is enlarged to form a button 282 having a central aperture 284 which receives the upper end of valve stem 262.

The chamber 276 is connected thru a passage 286 to the conduit 112 of Figure 1. The chamber 252 is connected by a passage 253 to the conduit 110 of Figure 1.

Valve 218 corresponds to valve 118 of Figure 1. It is opened by the fuel pressure differential across it in the same manner as valve 118. The diaphragm 219 performs the function of the piston 119 of Figure 1, and the spring 221 corresponds to the spring 121. It may be seen that the pressure in chamber 276, above the diaphragm, is the same as the pressure in conduit 112 and therefore the same as the pressure at the left side of the piston 119 in Figure 1. The pressure under the diaphragm 219 is the same as the pressure in the conduit 110, and therefore, the same as the pressure acting on the right face of the piston 119 in Figure 1.

The operation of valve 218 by springs 220 and 221 and diaphragm 219 corresponds fully to the operation of valve 118 by springs 120 and 121 and piston 119. It is believed that no further description of the operation of valve 218 is necessary.

Figure 3

Figure 3 shows a modified form of enrichment valve and control mechanism therefor, which may be substituted for the enrichment valve 118 of Figure 1. Figure 3 also shows diagrammatically a mixture control 58 and a jet system 60, which correspond to the same elements of Figure 1.

A carburetor body casting 300 is bored out to form a chamber 302. The lower end of chamber 302 opens into bore extending upwardly from the bottom of casting 300, which forms a chamber 304 in the casting 300. The upper end of chamber 302 is closed by an orifice plate or jet 306 provided with a downwardly extending rim forming a valve seat 308. The orifice plate 306 is provided with a central aperture thru which a valve stem 310 passes, and a plurality of circumferentially spaced orifices 312. A spring 314 is retained between the upper surface of the orifice plate 306 and a retainer 316 fixed on a stem 310.

A bushing 318 is inserted thru the chamber 304 and closes the communicating passage between chambers 302 and 304. The bushing 318 is provided with a central bore to receive a rod 320. A sleeve 322 slides on the outside of bushing 318 and extends upwardly therefrom. The sleeve 322 is provided near its center with a transverse wall 324 which is apertured to permit the passage of rod 320. A spring 326 is retained between the upper surface of bushing 318 and the wall 324, and biases the sleeve 322 upwardly into engagement with a flange 328 formed on the rod 320. The lower end of rod 320 is attached to the free end of a bellows 330, whose opposite end is fixed to the bushing 318. A passage 332 is bored thru the bushing 318 and the casting 300, and connects the interior of bellows 330 to the conduit 112 of Figure 1.

A cap 334 is threaded into the bore in casting 300 to close the lower end of chamber 304 and is provided with an upwardly extending sleeve portion 336 which maintains the bushing 318 in place. The sleeve 336 is apertured as at 338 so that the exterior of bellows 330 is exposed to the pressure in chamber 304, which is connected thru a passage 340 to the fuel line on the downstream side of the jet system. The bellows 330 may be provided with an internal spring 342, if desired.

Valve 311 corresponds generally to the valve 118 of Figure 1. The chamber 313 above the valve 311 is connected to conduit 110 thru a conduit 345. The chamber 302 on the downstream side of valve 311 is connected thru a conduit 347 to a chamber 319 in the jet system corresponding to the chamber 109 of Figure 1. The valve 311 is therefore subject to the same fuel pressure differential as the valve 118 of Figure 1.

When the mixture control is in its lean position, the pressure inside bellows 330 is substantially the same as the pressure outside the bellows 330. The spring 326 then causes bellows 330 to collapse, moving sleeve 322 upwardly into engagement with valve 311. Under such conditions, the fuel pressure differential must over-

come both the springs 314 and 326 to open the valve 311.

When the mixture control is moved to its rich position, the pressure inside bellows 330 is greater than the pressure outside, so that the bellows 330 is expanded to the position shown in the drawing, thereby carrying the rod 320 and spring 322 downward, separating the upper end of sleeve 322 from valve 311. Under those conditions, the fuel pressure differential then has only to overcome the spring 314 in order to open the valve 311.

It may, therefore, be seen that the particular value of fuel pressure differential which causes an opening of the enrichment valve 311 is smaller when the mixture control is in its lean position than when it is in its rich position.

While I have shown and described certain preferred embodiments of my invention, other modifications thereof will readily occur to those skilled in the art, and I therefore intend my invention to be limited only by the appended claims.

I claim as my invention:

1. A fuel supply system for an internal combustion engine, comprising a fuel conduit, three parallel branch passages in said conduit, a metering restriction in each of said branch passages, means for controlling the fuel pressure differential across said branch passages to control the fuel flow therethru, valve means movable in an opening direction in response to said fuel pressure differential for controlling the area of the restriction in one of said passages, spring means associated with said valve means for applying thereto a force acting in a valve closing direction, manually operable valve means for opening and closing another of said passages, means for applying an additional force to said pressure responsive valve means, means for controlling said force applying means including an expandible chamber having a movable wall, means connecting the interior of said chamber to said other passage between said valve means and the restriction therein, said wall being moved to control the application and removal of said additional force from said pressure responsive valve means in response to changes in pressure in said chamber due to operation of said manual valve means and thereby to vary the resultant of the forces applied to said pressure responsive valve means so that it opens at different values of said fuel pressure differential, depending upon whether said manual valve means is open or closed.

2. A fuel supply system for an internal combustion engine, comprising a fuel conduit, three parallel branch passages in said conduit, a metering restriction in each of said branch passages, means for controlling the fuel pressure differential across said branch passages to control the fuel flow therethru, a valve movable in an opening direction in response to said fuel pressure differential for controlling the area of the restriction in one of said passages, first spring means biasing said valve to closed position, second spring means coacting with said first spring means, manually operable valve means for opening and closing another of said passages, and means responsive to the pressure in said other passage between said manual valve means and the restriction therein for restraining said second spring means to vary the force acting on said pressure responsive valve so that it opens at different values of said fuel pressure differential, depend-

ing upon whether said manual valve means is open or closed.

3. A fuel supply system for an internal combustion engine, comprising a fuel conduit, three parallel branch passages in said conduit, a metering restriction in each of said branch passages, means for controlling the fuel pressure differential across said branch passages to control the fuel flow therethru, a valve movable in an opening direction in response to said fuel pressure differential for controlling the area of the restriction in one of said passages, spring means biasing said valve to closed position, manually operable valve means for opening and closing another of said passages, and means responsive to the pressure in said other passage between said valve means and said restriction therein to vary the biasing force acting on said pressure responsive valve so that it opens at different values of said fuel pressure differential, depending upon whether said manual valve means is open or closed.

4. A fuel supply system for an internal combustion engine, comprising a fuel conduit, three parallel branch passages in said conduit, a metering restriction in each of said branch passages, means for controlling the fuel pressure differential across said branch passages to control the fuel flow therethru, a valve movable in an opening direction in response to said fuel pressure differential for controlling the area of the restriction in one of said passages, a stem for said valve, first spring means biasing said valve to closed position, manually operable valve means for opening and closing another of said passages, an expansible chamber having a movable wall aligned with said valve stem, second spring means in said chamber biasing said wall into engagement with said stem and effective to oppose said first spring means when said wall engages said stem, means connecting the interior of said chamber to said other passage between said valve means and the restriction therein, the exterior of said wall being subject to the pressure on the upstream side of the restriction in said one passage, said wall moving in response to a decrease in pressure in said chamber due to closure of said manual valve means to disengage said valve stem and thereby to increase the net force biasing said valve closed so that it opens at a higher value of said fuel pressure differential when said manual valve means is closed than when it is open.

5. A fuel supply system for an internal combustion engine, comprising a fuel conduit, three parallel branch passages in said conduit, a metering restriction in each of said branch passages, means for controlling the fuel pressure differential across said branch passages to control the fuel flow therethru, a valve movable in an opening direction in response to said fuel pressure differential for controlling the area of the restriction in one of said passages, a stem for said valve, first spring means biasing said valve to closed position, manually operable valve means for opening and closing another of said passages, an expansible chamber, a flexible diaphragm forming one wall of said chamber and aligned with said valve stem, a button carried by said diaphragm and recessed to receive the end of said stem, second spring means in said chamber biasing said diaphragm and button into engagement with said stem and effective to oppose said first spring means when said button engages said stem, means connecting the interior of said chamber to said other passage between said valve

means and the restriction therein, the exterior of said diaphragm being subject to the pressure on the upstream side of the restriction in said one passage, said diaphragm moving in response to a decrease in pressure in said chamber due to closure of said manual valve means to disengage said valve stem and thereby to increase the net force biasing said valve closed so that it opens at a higher value of said fuel pressure differential when said manual valve means is closed than when it is open.

6. A fuel supply system for an internal combustion engine, comprising a fuel conduit, three parallel branch passages in said conduit, a metering restriction in each of said branch passages, means for controlling the fuel pressure differential across said branch passages to control the fuel flow therethru, a valve movable in an opening direction in response to said fuel pressure differential for controlling the area of the restriction in one of said passages, a stem for said valve, first spring means biasing said valve to closed position, manually operable valve means for opening and closing another of said passages, a cylinder, a piston movable in said cylinder and aligned with said valve stem, second spring means in said cylinder biasing said piston into engagement with said stem and effective to oppose said first spring means when said piston engages said stem, means connecting the interior of said cylinder to said other passage between said valve means and the restriction therein, the exterior of said piston being subject to the pressure on the upstream side of the restriction in said one passage, said piston moving in response to a decrease in pressure in said cylinder due to closure of said manual valve means to disengage said valve stem and thereby to increase the net force biasing said valve closed so that it opens at a higher value of said fuel pressure differential when said manual valve means is closed than when it is open.

7. Valve mechanism for controlling the flow thru three parallel passages leading from a common inlet to a common outlet, each passage having a restriction therein, said valve mechanism comprising a first valve located in a second of said passages and movable in an opening direction in response to a predetermined fluid pressure differential across said restrictions for augmenting the flow thru one of said passages, spring means associated with said first valve for applying thereto a force acting in a valve closing direction, a manually operable valve for opening and closing a third of said passages, means for applying an additional force to said first valve, means for controlling said force applying means including an expansible chamber having a movable wall, means connecting the interior of said chamber to said third passage between the manually operable valve and the restriction therein, said wall being moved to control the application and removal of said additional force from said first valve in response to changes in pressure in said chamber due to operation of said manual valve and thereby to vary the resultant of the forces applied to said first valve so that it opens at different values of said fluid pressure differential, depending upon whether said manually operable valve is open or closed.

8. Valve mechanism for controlling the flow thru three parallel passages leading from a common inlet to a common outlet, each passage having a restriction therein, said valve mechanism comprising a first valve located in a second of said passages and movable in an opening direc-

11

tion in response to a predetermined fluid pressure differential across said restrictions for augmenting the flow thru one of said passages, spring means associated with said first valve for applying thereto a force acting in a valve closing direction, a manually operable valve for opening and closing a third of said passages, and means responsive to the pressure in said third passage between said manually operable valve and the restriction therein to vary the biasing force acting on said first valve so that it opens at different values of said fluid pressure differential, depending upon whether said manually operable valve is open or closed.

9. Valve mechanism for controlling the flow thru three parallel passages leading from a common inlet to a common outlet, each passage having a restriction therein, said valve mechanism comprising a first valve located in a second of said passages and movable in an opening direction in response to a predetermined fluid pressure differential across said restrictions for augmenting the flow thru one of said passages, a stem for said valve, first spring means biasing said valve to closed position, manually operable valve means for opening and closing a third of said passages, an expansible chamber, a flexible diaphragm forming one wall of said chamber and aligned with said valve stem, a button carried by said diaphragm and recessed to receive the end of said stem, second spring means in said cham-

12

ber biasing said diaphragm and button into engagement with said stem and effective to oppose said first spring means when said button engages said stem, means connecting the interior of said chamber to said third passage between said valve means and the restriction therein, the exterior of said diaphragm being subject to the pressure on the upstream side of the restriction in said one passage, said diaphragm moving in response to a decrease in pressure in said chamber due to closure of said manual valve means to disengage said valve stem and thereby to increase the net force biasing said valve closed so that it opens at a higher value of said fluid pressure differential when said manual valve means is closed than when it is open.
